W. A. HOMAN

COPYHOLDER

Inventor

W. A. HOMAN.

884 Attorney

UNITED STATES PATENT OFFICE.

WALTER A. HOMAN, OF DENVER, COLORADO, ASSIGNOR TO THE HOMAN COPY HOLDER COMPANY, A CORPORATION OF COLORADO.

COPYHOLDER.

Application filed August 18, 1922. Serial No. 582,677.

To all whom it may concern:

Be it known that I, WALTER A. HOMAN, a citizen of the United States, residing at the city and county of Denver and State of Colorado, have invented certain new and useful Improvements in Copyholders; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to copy holders of the type employed in connection with typewriters.

It is well known that it is necessary for efficient typewriting to have some means of holding the copy where it can be conveniently seen. Many different kinds of copy holders have been invented and offered for sale, and yet it is obvious that very few of them are in use, which would indicate that 25 the present copy holders are defective in some important particular.

It is the object of this invention to produce a copy holder that shall be free from most of the serious faults of those heretofore employed. It is evident that the copy to be followed should be held in such a position that the operator's head and eyes need not constantly be shifted in order to see the copy and to observe the workings of the 30 machine. It is also very important that the copy shall be supported in such a position with respect to the machine that the focus of the eyes need not be appreciably changed when shifting from the copy to the machine, 35 and vice versa. It is the object of this invention to devise a copy holder that shall embody both of the characteristics referred to above and which shall at the same time permit the copy to be conveniently placed 40 therein and removed therefrom; which shall permit a new page of copy to be quickly and conveniently exposed, and which shall be of simple design and neat appearance. The above advantages, and others which will 45 appear as the description proceeds, are obtained by means of a construction which I will now describe, reference being had for

this purpose to the accompanying drawing, in which

Fig. 1 shows a front elevation of a typewriter equipped with my improved copy holder;

Fig. 2 shows a side elevation of a typewriter equipped with my copy holder;

Fig. 3 is a broken side elevation of a portion of my copy holder;

Fig. 4 is a section taken on line 4—4, Fig. 3;

Fig. 5 is a front elevation of a modification; and

Fig. 6 is an end elevation of the form shown in Fig. 5.

Numeral 1 represents a typewriter of well known make having a keyboard 2 and a platen 3. To one of the sides 4 of the typewriter framework I secure a copy holder supporting bracket, which consists of a clamping member 5 provided with a set screw 6. To the bottom of the clamp 5 I secure a base member 7, to the outer end of which I fasten a vertical tubular member 8, which is adapted to receive the vertical portion 9 of the copy holder supporting member 10. A screw 11 passes through the tubular member 8 and serves as a stop or support for the end of the vertical member 9. A plurality of holes 12 may be provided, if desired, so that the height of the holder can be adjusted to fit any type of typewriting machine. Rotatably and slidably connected to the supporting member 10 is a cylindrical copy holding member which consists of a cylinder 13 having opposed end members 14 soldered or otherwise secured thereto. A tubular member 15 extends axially through the cylinder 13 and serves as a bearing for co-operating with the rod 10. The cylinder 13 is provided near each end thereof with two angularly spaced openings 16 for a purpose which will hereinafter appear. Cylinder 13 is of such a diameter that the circumference thereof exceeds the length of the paper which is to be secured thereto. For the purpose of holding the copy in place on the cylinder, I provide two clamping members 17 and 18 which are arcuate in cross section and have end portions 19 which extend inwardly through the slots 16. To the ends of

95
100

the inwardly extending portions 19 I connect springs 20, which are provided with hooks 21 which engage the tube 15 in the manner shown in Fig. 4. Springs 20 are 5 under tension and tend to keep the two edges of the clamping members against the surface of the cylinder. Secured to each clamping member is a finger 22, by means of which the clamping members may be rocked about one 10 edge.

When the copy 23 is to be secured to the cylinder, the lower edge of clamping member 18 is raised from the surface of the cylinder and the upper edge of the copy inserted therebetween. The lower end of the copy is then wrapped around the cylinder and clamped beneath the upper edge of clamping member 17 in the manner clearly indicated in Figs. 2 and 4. Clamping member 17 is provided with a cutout portion 24, into which the thumb can be inserted whenever a new page is to be exposed. Pivotally connected to the supporting rod 10 are two plate-like members 25, which have a portion 20 26 thereof extending beyond the outer circumference of the cylinder. These projecting ends are connected by a bar 27 which serves as an indicator or guide. In order to prevent the plates 25 from rotating with 25 the cylinder and also for the purpose of moving the same on the rod 10 in accordance with the movement of the carriage and platen 3, I secure to or form integral with the plates 25 downwardly extending arms 28, 30 which are provided at their lower ends with a slot 29, which engages the platen bearing 30 just inside of the knobs 31. Arms 28 are either made entirely of resilient material and of such thickness that they yield 35 slightly as the carriage moves, or they may have a resilient portion 32 which yields. The object in making the arms 28 yielding is that by this means the intermittent movement of the carriage will cause a constant 40 movement of the copyholder, for the reason that there is considerable friction between the tube 15 and the rod 10, and that there is considerable inertia inherent in the copyholder and therefore it will lag slightly behind the movements of the carriage when 45 the arms connecting the two are resilient. I consider this to be an important feature of my invention and therefore desire to emphasize it.

50 In Figs. 5 and 6 I have shown a slightly modified embodiment of my invention. In this modified form the plates 25^a are each provided with an outstanding ear 33, to which is pivotally secured an indicator 34, 55 whose upper edge rests on the copy and indicates the line to be copied.

The plates 25^a, instead of having an integral arm 28 connected thereto, have similar arms 28^a secured thereto by means of a clamping screw 35. Arms 28^a, like arms 28,

have slots 29 that engage the spindle 30 and are also made resilient in the manner above explained. The object of making arms 28^a movable with respect to plates 25^a is to secure a slight adjustment of the level of the indicator 34, as this may be desirable in order to secure the most comfortable arrangement.

The operation of my device is as follows. The copy 23 is secured in place beneath the 75 clamping edges of the members 17 and 18. The cylinder 13 is then rotated on the axle 10 until the first line appears above the bar 27. The carriage is moved into the proper 80 position for commencing and then the matter contained in the line referred to is copied. When a line of the manuscript has been copied the operator merely moves the cylinder 13 a distance sufficient to bring a new line into position. Where the copy is 85 a typewritten one, the typewriter will have to be adjusted for a new line at the end of each line of copy, but where a manuscript is to be copied, this relation does not necessarily exist. Where the copy is typewritten, it is desirable that the copyholder move in unison with the carriage, as by this means the word to be copied will be directly over the place where the printing takes place and the operator can see one or the other by merely moving the eyes a slight distance up and down. Where the copy is in longhand or in shorthand, it is not essential that the copy move with the carriage, but as a rule it causes no inconvenience and is therefore not objectionable. I wish, at this point, to call attention to the fact that since the copy 23 occupies a position directly above the platen, the distance of the two from the operator's eyes is substantially equal and therefore the eye does not require to change its focus in looking from the one to the other as is invariably necessary where the copy is laid on the table or supported to the rear of the machine. When paper is to 100 be inserted into the typewriter or when, for any other reason, it is desirable to move the copyholder out of the way, the supporting rod 10 may be raised sufficiently to remove the arm 28 from the spindle 30. The copyholder may then be rotated about the part 9 so as to be out of the way. When a page of copy has been written, the operator merely places his thumb in the cut-out portion 24 and presses slightly on the finger 22. A page is then peeled off from the copy and is turned over so as to expose a new 105 page.

From the above it is apparent that I have produced an improved copyholder that is 110 so designed that the copy is held in a position directly over the platen so that the distance to either is so nearly equal that the eye will not have to change its focus as the operator looks from one to the other. My 115

improved copyholder is also constructed so that it moves with the carriage and has means whereby the intermittent motion of the latter produces a continuous movement 5 of the former. My copyholder can be quickly and conveniently moved out of the way and is so designed that the copy may be easily and quickly shifted so as to present a new page.

Having now described my invention, what I claim is:

1. A copyholder comprising a cylindrical member having a pair of clamping members secured thereto, a horizontal supporting member, means for slidably and rotatably securing the cylindrical member thereto, and means for permitting the supporting member to be rotated about a vertical axis.

2. A copyholder comprising, in combination, a cylindrical copyholding member, means for securing the copy to the outside thereof, and means for slidably and rotatably supporting said copyholding member.

3. A copyholder comprising, in combination, a cylindrical copyholding member, means for securing the copy to the outside thereof, and means for slidably and rotatably supporting said copyholding member, and means for permitting said copyholder 30 to be rotated about a vertical axis.

4. In combination, a typewriter having a movable carriage, a copyholder, means for slidably and rotatably supporting said copyholder in operative relation to the typewriter, and means connected to said holder and engaging said carriage whereby the movements of the latter will cause a corresponding movement of the former.

5. In combination, a typewriter having a 40 movable carriage, a copyholder, means for slidably and rotatably supporting said copyholder in operative relation to the typewriter, and means connected to said holder and engagaing said carriage whereby the 45 movements of the latter will cause a corresponding movement of the former, said

means being resilient whereby the intermittent movements of the carriage will cause a substantially uniform movement of the latter.

6. In combination, a typewriter having a 50 movable carriage, a bracket secured to the typewriter, a horizontal bearing member secured to the bracket by means which permit the bearing member to rotate in a horizontal 55 plane, a cylindrical copy holding member rotatably and slidably secured to said bearing member, and resilient means for causing said copy holder to move in accordance with the movement of the carriage.

7. A copy-holding member comprising a 60 bearing member, a cylindrical copy-holder slidably and rotatably secured thereto, a pair of spaced clamping members secured to said cylinder, resilient means for holding said clamping members in place, a plate secured to each end of said cylinder, an indicating member joining said plates, and means secured to said plates and extending to the carriage for transmitting the movement of 70 the latter thereto.

8. A copy-holding member comprising a 75 bearing member, a cylindrical copy-holder slidably and rotatably secured thereto, a pair of spaced clamping members secured to said cylinder, resilient means for holding said clamping members in place, a plate secured to each end of said cylinder, an indicating member joining said plates, and means secured to said plates and extending to the 80 carriage for transmitting the movement of the latter thereto, said means being adjustable with respect to the plates.

9. A cylindrical copy-holding member 85 having longitudinal arcuate clamping members secured thereto, and resilient means for securing said clamping members in place, with both edges thereof contacting with the surface of the cylinder.

In testimony whereof I affix my signature.

WALTER A. HOMAN.
